CLAIM

The ornamental design for a glucose meter, as shown and described.

DESCRIPTION

FIG. 1 is a perspective view of a glucose meter showing our new design;

FIG. 2 is a top view thereof;

FIG. 3 is a front view thereof;

FIG. 4 is a right side view thereof, the left side view being a mirror image;

FIG. 5 is a rear view thereof; and,

FIG. 6 is a bottom view thereof.

The broken lines illustrate unclaimed portions of the glucose meter and form no part of the claimed design.
